[57] CLAIM

The ornamental design for an article of jewelry, as shown and described.

DESCRIPTION

FIG. 1 is a front profile view of the article of jewelry showing a textured surface in the form of a fingerprint; FIG. 2 is a right side profile view of the article of jewelry, the left side being a mirror image thereof;

FIG. 3 is a cross sectional view to better illustrate the textured surface in the form of a fingerprint;

FIG. 4 is a rear planer view of the article of jewelry;

FIG. 5 is a bottom planer view of the article of jewelry illustrated in FIG. 4;

FIG. 6 is a top elevation view of the article of jewelry as illustrated in FIG. 4; and,

FIG. 7 is an alternative embodiment in combination with an encircling jewelry article.
